UNITED STATES PATENT OFFICE.

ARTHUR LEE LIGON, OF KILLEEN, TEXAS.

DEEP-WELL PUMP.

1,332,672.

Specification of Letters Patent.

Patented Mar. 2, 1920.

Application filed October 30, 1917, Serial No. 199,241. Renewed October 9, 1919. Serial No. 329,647.

To all whom it may concern:

Be it known that I, ARTHUR LEE LIGON, a citizen of the United States, residing at Killeen, in the county of Bell and State of Texas, have invented certain new and useful Improvements in Deep-Well Pumps, of which the following is a specification.

My invention has relation to an improvement in deep well pumps of particularly that type or class wherein the working barrel and other accessories of the pump are adapted to be inserted at the proper point in a well casing and to be withdrawn readily therefrom for the purpose of repairs or renewal of parts, and in such connection it relates more particularly to an improvement upon the pump described and claimed in my former Patents #1,073,257 of September 16, 1913, No. 1,120,820 of December 15, 1914, and No. 1,223,498 of April 24, 1917.

To this end my invention broadly considered consists in the provision of means whereby without removal from the well the ordinary well casing may be adapted to readily support the pump barrel at the required distance above the fluid to be pumped and to readily support the seats for the necessary valves used in such pump structures. In my previous Patent #1,223,498 of April 24, 1917, the couplings between sections of the well casing were utilized for these purposes and in the driving of new wells such a casing with its peculiar couplings can be used. However it is the principal object of my present invention to devise means whereby the well casing of ordinary construction and already installed can be fitted and arranged to support a removable pump barrel and to support the seats for the pump without withdrawing the casing and installing new pipe with improved couplings.

The nature and scope of my invention will be more fully understood from the following description taken in connection with the accompanying drawings forming part hereof, in which—

Figure 1 is a vertical sectional view of a well casing and pump embodying the main features of my invention.

Fig. 2 is a similar view of the well casing and upper and lower seats, with the pump barrel removed.

Fig. 3 is a similar view of the pump barrel removed from the casing.

Fig. 4 is a view similar to Fig. 1, but illustrating a modified form of my invention.

Fig. 5 is a view similar to Fig. 4 but with the pump barrel removed, and

Fig. 6 is a vertical sectional view of the pump barrel of Fig. 4 removed from the well casing.

Referring to the drawings and particularly to Figs. 1, 2 and 3 which illustrate a pump for relatively shallow wells, 1 represents one of the sections of a well casing differing only from the ordinary well casing in the following two respects, namely:

At the top or upper end of each section 70 the inner wall of the casing is shaped or deformed to receive and firmly hold a sleeve 2 which is driven into place and has intermediate of its ends an outward bulge 3 fitting into a corresponding channel in the interior 75 of the casing. When so driven into the casing the sleeve 2 becomes a part of the casing decreasing but slightly the regulation interior diameter of said casing.

At the lower end of each section the inner 80 wall is screw-threaded to receive, if required, a thimble 4 having its interior frusto-conical to form a seat for the conical valve 5 carried at the lower end of the pump barrel 6.

In the drawings only that section of the casing 1 which incloses the pump barrel 6 is illustrated and this section of necessity is provided at its lower end with the thimble 4 constituting the seat for valve 5. The other 90 sections of the casing may if desired be provided with the upper sleeve 2 but the lower thimble 4 will be absent.

To the top of the pump barrel 6 is screw-threaded a short tube 7 provided on that 95 portion of its periphery which projects above the pump with one or more leaf springs 8. Each spring 8 is united or otherwise secured at its upper end, as at 9, to the tube 7 and the body of the spring is bent 100 outward as at 10 to slide into and out of the bulged portion 3 of the sleeve 2. When the barrel 6 is properly seated in casing 1 it is firmly supported by the springs 8 of tube 7 in the casing itself or in the sleeve 2 of the 105 casing.

In the form of my device illustrated in Figs. 1 to 3, the casing 1 must be shaped and formed on its interior at either end to receive respectively the sleeve 2 and the thimble 4 110

- which coöperate with parts or accessories to the pump barrel 6 in the proper support and seating of said pump barrel. In other words in this form of my device the interior 5 wall of the casing after being modified or altered slightly will receive and support the pump barrel so that said barrel may be placed in position or removed without displacement or disarrangement of the casing.
- 10 In Figs. 4, 5 and 6 which illustrate a pump for deep wells the construction is such that the interior wall of the casing 1 is unchanged and unaltered from the ordinary form of casing yet will support and seat the pump barrel 6 and its valve 5. In this form 15 of my device the valve seat consists of a frusto-conical thimble 14 having a tubular extension 15 at its base which extends some distance into a sleeve 16. The lower end of 20 the sleeve 16 is provided on its periphery with one or more bow springs 17 which serve to fit the sleeve 16 relatively tight into the interior of the casing 1. Above these springs 17 the body of the sleeve 16 is slotted and 25 through one or more of these slots one or more gripping bars 18 project, the upper end of each bar 18 being riveted or otherwise fastened to the interior of the sleeve 16.
- The tubular extension 15 has its periphery 30 contoured to form a wedge in cross-section and fits against the back of the bars 18. When now the thimble 14 with its extension 15 is pressed downward in the sleeve 16 (as under the weight of the supported pump 35 barrel 6 and its valve 5), the bars 18 are pressed outward to firmly grip the interior wall of the casing 1, and thus resist effectively any tendency to dislodge the sleeve 16 and the supported valve seat 14 from the 40 position it is to occupy in the casing. To take up for minute variations of pressure of the valve 5 in the thimble 14, said thimble 14 traverses a packing ring 19 located upon the upper edge of the sleeve 16. This packing ring 19 serves also to prevent leakage of sand or water into the space between the 45 pump barrel 6 and casing 1.
- The tubular extension 15 projects in the form of a slotted tubular base 20; the slots 50 21 of which being in alinement with the grip bars 18. When now for the purpose of removal of the seat from the casing the thimble 14, extension 15 and base 20 are pulled upward, the base 20 is raised to a position 55 opposite the grip bars 18 so that they may spring upward through slots 21 and thus release the sleeve 16 from engagement with casing 1 and to lock the sleeve 16 to the base 20 carried by the valve seat 14 and its extension 15. It follows from this description 60 that a downward movement of thimble 14 in sleeve 16 will serve to throw the grip bars 18 against the casing whereas an upward movement of said thimble 14 in sleeve 16 65 will first permit of release of grip bars 18

from the casing and thereafter the interlocking of the sleeve 16 with the base 20 through the grip bars 18 and slots 21.

The upper end of the pump barrel 6 is provided with a similar means for gripping 70 said end of the barrel to the interior of casing 1. Thus in the upper end of the barrel 6 is screw-threaded or otherwise removably secured a sleeve 26 (corresponding to sleeve 16 of the lower seat). The sleeve 26 is provided with one or more grip bars 28 arranged to be forced outward by the tubular extension 25 of a thimble 24. When the thimble 24 is raised the grip bars 28 will fall into the slots 31 of the tubular base 30 below 80 extension 25. A packing ring 29 on the exterior of thimble 24 serves to prevent sand and water, falling into the space between barrel 6 and casing 1.

In the form illustrated in Figs. 4, 5 and 6 85 the piston of the pump (not shown) is similar to that illustrated in Fig. 1 and reciprocates in the barrel 6 below the base 30 and above the valve 5. When the pump barrel 6 is to be withdrawn from the casing; the piston with its rod is pulled upward against this base 30 to elevate the thimble 24 and to release the grip bars 28. Thereafter the pump barrel may be drawn upward through the casing. When the pump barrel has been 90 removed a tool may be inserted to grip the lower thimble 14, and when said thimble is slightly elevated the grip bars 18 are released from the casing and the seat for valve 5 may thereafter be drawn upward through 95 and out of the casing.

In Figs. 1, 2 and 3 a pull on the pump rod will dislodge the flat leaf springs 8 from the bulged portion of sleeve 3 and thereafter the pump barrel can be readily removed from 100 the casing. In this form of pump the seat or lower thimble 4 is not removed from the casing.

Having thus described the nature and objects of my invention, what I claim as new 110 and desire to secure by Letters Patent is—

1. In a pump, a section of well casing, a pump barrel inclosed therein, a means for detachably supporting the upper end of said barrel upon the interior of the casing, a valve carried by the pump barrel, a valve seat consisting of a thimble, tubular extension and a slotted base, a sleeve into which the extension and base project, a grip bar carried by the sleeve and arranged to traverse the sleeve outward to grip the casing when the extension and thimble are projected into said sleeve. 115

2. In a pump, a section of well casing, a pump barrel inclosed therein, a means for 120 detachably supporting the upper end of said barrel upon the interior of the casing, a valve carried by the pump barrel, a valve seat consisting of a thimble, tubular extension and a slotted base, a sleeve into which 125

the extension and base project, a grip bar carried by the sleeve and arranged to traverse the sleeve outward to grip the casing when the extension and thimble are projected into said sleeve, and said bar arranged to spring inward into the slotted base when the base extension and thimble are drawn out of said sleeve.

5. In a pump, a section of casing, a pump barrel inclosed therein, a sleeve detachably secured to the upper end of the pump barrel, a grip bar secured at one end to the interior

of the sleeve and having its body arranged to project through a slot in the sleeve, a thimble, tubular extension and slotted base 15 arranged to project through said sleeve to extend the grip bar outward from the sleeve into locking engagement with the casing and to be withdrawn from said sleeve to release the grip bar from the casing and to 20 interlock the same with said slotted base.

In testimony whereof I have signed my name to this specification.

ARTHUR LEE LIGON.
